(74) Attorney, Agent, or Firm — Thomas | Horstemeyer,
LLP(57) **CLAIM**

The ornamental design for a fluid dispenser, as shown and described.

DESCRIPTION

1.1 is a front elevational view of fluid dispenser showing my new design;

1.2 is a perspective view thereof showing the fluid dispenser in an expanded position;

1.3 is a top view thereof;

1.4 is side elevational view thereof; and

1.5 is a perspective view thereof showing the fluid dispenser in a compressed position.

The broken lines in the reproductions and the structure shown shaded in solid black in 1.2 illustrate portions of the fluid dispenser that form no part of the claimed design.
